EASY-POUR GALLON SUPPORTER

Hideo Okunami, Honokaa, Territory of Hawaii

Application September 28, 1948, Serial No. 51,522

1 Claim. (Cl. 248—141)

1

This invention relates to supporting cradles for large jugs and bottles to facilitate pouring therefrom, and particularly to such a device which I prefer to term an "Easy-Pour Gallon Supporter."

The main object of my invention is to provide a convenient means for facilitating the pouring of liquids from large jugs and bottles, and especially a gallon jug or bottle.

Another object is to provide a rocking supporting cradle for a gallon jug or the like which is pivotally mounted on a stationary base.

A further object is to provide such a rocking support or cradle for a jug or bottle which so completely and safely supports the jug mounted thereon that only the fingers are required to tilt the jug and pour therefrom, so that, in fact, a child is easily able to pour from the jug.

It is also an object to have such a pivoted rocking support or cradle for a jug or bottle which holds the latter in well balanced condition to provide ready tilting action therefor and which is also light and portable so that the device may be placed on any table or platform and thus be accessible for easily pouring fluid therefrom without danger of spilling.

A practical object is to make the device as a whole of metal rods bent and secured together to facilitate manufacture, and to provide the resulting ensemble with a spring to retain the finger hold on the bottle and thereby hold the latter safely in position without danger of dropping off the device.

Other objects and advantages of the invention will appear in further detail as the specification proceeds.

In order to facilitate ready comprehension of this invention for a proper appreciation of the salient features thereof, the invention is illustrated on the accompanying drawing forming part hereof, and in which:

Figure 1 is a side elevation of an easy-pour gallon supporter or cradle made according to the invention and embodying the same in a practical form, the device being shown in operative position supporting a gallon bottle or jug;

Figure 2 is a front elevation of the same device without the bottle or jug and appearing as seen from the left in Figure 1;

Figure 3 is a side elevation of the bottle or jug supporter of Figure 1, showing the rocking cradle portion tilted with the bottle thereon in position for pouring from the bottle;

Figure 4 is a perspective view of the gallon bottle or jug supporter alone.

In the views, the same reference numerals indicate the same or like parts.

2

Large bottles and jugs are notoriously clumsy and inconvenient to handle in the home or the laboratory, and especially does it require strength and experience to pour liquids from such containers without spilling, not to mention that both hands are imperatively required for such a task. Many liquids used are most economically obtained in bottles and jugs of large size, so that they are frequently used despite the difficulty encountered in handling them.

Upon considering this problem, it has occurred to me that a container of large size should be mounted on a support capable of rocking in such manner as to allow a balanced tilting of the container and thereby eliminate the difficulty of handling the latter when pouring therefrom. As a result, I have found it quite feasible to produce a device for this purpose which will now be more fully described.

Hence, in the practice of my invention, and referring again to the drawing, a jug or bottle supporter, generally indicated at 5, primarily includes a base consisting of a bottom loop 6 having a pair of upwardly and rearwardly-inclined supporting arms 7, 7 bent upwardly to form the upright ends 8, 8 terminating in eyes or bearing loops 9, 9.

Rotatably mounted in the eyes or bearing loops 9, 9 are a pair of short pivot shafts 10, 10 projecting outwardly therethrough and integral with a pair of depending vertical side bars 11, 11 which at the bottom are bent to form a horizontal or transverse rest bar 12 with which they are integral. Secured to the upper ends of the vertical side bars 11, 11 and the pivot shafts 10, 10 is a top ring 13 preferably welded or brazed to the mentioned side bars and pivot shafts, and having the forward ends 14, 14 open and bent to form two depending guide projections 15, 15 serving to assist in holding a bottle upright between the vertical side bars 11, 11. At the rear of the open ring 13 is fixed a rear bar 16 by welding or brazing to the lower surface thereof, this bar 16 being bent outwardly at 17 to provide a handle and at the bottom being bent forwardly in horizontal direction to form an auxiliary rest bar 18 which at the forward end thereof is brazed or welded to the intermediate portion of the transverse rest bar 12 already described, the two rest bars 12 and 18 serving to support the bottom of a bottle 19, while the top ring 13 encircles the major portion of the circumference thereof and virtually forms a clamp for retaining the same in position on the rest bars.

In order to determine the safe and proper position for the bottle 19 in the rocking cradle formed

by the top ring 13, as well as the vertical side bars 11, 11, the rear bar 16 with its handle 17, the bottom rest bars 12 and 18 and pivot shafts 10, 10 rotatably mounted in the bearing loops or eyes 9, 9, primarily the rearwardly-extending rest bar 18 is provided with an upwardly-bent stop 20 intermediate the mentioned bar 18 and handle 17 to prevent the lower portion or bottom 21 of bottle 19 from being displaced rearwardly into the handle portion 17. In addition, a tension spring 22 is provided at one end with a loop 23 encircling the rear portion of top ring 13, and at the other end has a second loop 24 to which is connected an eye 25 of a hook 26. The mentioned hook 26 is adapted to engage in the finger hold 27. When the bottle 19 is lowered through the upper encircling ring 13 to bring the bottom 21 into supporting contact with the bottom rest bars 12 and 18, the depending guide portions or projections 15, 15 on the front ends 14, 14 of ring 13 will tend to guide the bottle into true vertical position with respect to the vertical side bars 11, 11 and will, of course, serve also to retain the bottle within ring 13. When the hook 26 secured to the free end of anchoring spring 22 is hooked into the finger ring or hold 27 on the bottle, this spring will anchor the upper end of the bottle and prevent the same effectively from forcibly opening the ends 14, 14 of ring 13 apart by its weight when the device is tilted and will thus safely hold the bottle in position upon the rest bars 12 and 18 between side bars 11, 11, and within the confines of ring 13.

The arrangement is such that when it is desired to tilt bottle 19 to pour from the neck 28 thereof, it is merely necessary to grasp the handle 17 with one hand and tilt the entire structure integral with or rigidly secured to the end shafts 10, 10 and the vertical side bars 11, 11, as indicated in Figure 3, when it will be found that the bottle 19 is so well balanced that it requires but slight effort to lift handle 17 and thereby tilt the bottle in such fashion as to readily pour from its neck 28, changing the level of the liquid at 29, as indicated in Figure 1, to that indicated at 30 in Figure 3. It may thus be considered that the invention includes a stationary base 6 with its inclined upwardly-projecting arms 7, 7 bent at their upper ends into vertical short arms 8, 8 terminating in the bearings or eyes 9, 9 on the one hand, while the rest of the structure suspended upon the pivot shafts 10, 10 which extend outwardly through the mentioned bearings or eyes 9, 9 constitutes a rocking supporting cradle for the bottle or jug involved.

Manifestly, variations may be resorted to and

parts and features may be modified or used without others within the scope of the appended claim.

Having now fully described my invention, I

5 claim:

A bottle or jug support for facilitating pouring from the bottle or jug, including a stationary base consisting of a flat horizontal open loop with a pair of rigid and rearwardly-inclined integral supporting arms extending upwardly from said open loop and bent directly upward at the upper portions to form vertical ends terminating in a pair of opposite eyes serving as pivot bearings, and a rocking cradle rockably mounted on said base and comprising a top ring which is open at the forward portion of the cradle and terminates in a pair of downwardly-directed or pendent guiding projections spaced apart, said top ring being adapted to encircle an intermediate portion of a bottle having an upper neck portion and a finger hold or ring secured adjacent to the neck portion, a pair of pivot shafts secured to the exterior sides of the top ring and extending rotatably into the eyes or pivot bearings on said arms, a transverse bottom rest bar for supporting the bottle or jug, a pair of vertical side bars extending integrally upward from the ends of the transverse bottom rest bar and secured at the upper ends thereof to the top ring at the junctions thereof with said pivot shafts, a rear handle portion secured at the upper end thereof to the rear portion of said top ring and having an intermediate rearwardly-projecting portion adapted to be grasped by the fingers, a forwardly-directed auxiliary rest bar integrally secured at the rear end thereof to the lower portion of said handle member and at the forward end secured to the intermediate portion of the transverse bottom rest bar, and an anchoring tension spring connected at one end to the rear portion of said top ring and at the other end carrying a hook for engaging with the finger hold on said bottle when the latter is mounted in said cradle.

HIDEO OKUNAMI.
